UNITED STATES PATENT OFFICE

121,667

DESIGN FOR A STRETCHER FOR DOILIES, SCARFS, SWEATERS, OR LIKE ARTICLES

Ernst A. Bartsch, Chicago, Ill., assignor of one-half to Arthur J. Kuhn, Chicago, Ill.

Application June 15, 1940, Serial No. 93,024

Term of patent 14 years

To all whom it may concern:

Be it known that I, Ernst A. Bartsch, a citizen of the United States, residing at Chicago, in the county of Cook and State of Illinois, have invented a new, original, and ornamental Design for a Stretcher for Doilies, Scarfs, Sweaters, or Like Articles, of which the following is a specification, reference being had to the accompanying drawing, forming a part thereof in which

Fig. 1 is a top plan view of a stretcher for doilies, scarfs, sweaters, or like articles embodying my new design; and

Fig. 2 is an edge elevational view thereof.

I claim:

The ornamental design for a stretcher for doilies, scarfs, sweaters, or like articles, substantially as shown.

ERNST A. BARTSCH,
